INVENTOR

BY *Victor J. Evans*

ATTORNEY

UNITED STATES PATENT OFFICE

RUDOLPH H. GUENTHER, OF CHICAGO, ILLINOIS

HEATING DEVICE

Application filed November 22, 1927. Serial No. 235,107.

This invention relates to certain novel improvements in heating devices and has for its principal object the provision of an improved construction of this character which will be 5 highly efficient in use and economical in manufacture.

Among the several objects of the invention is to provide a simple arrangement by which the cool air adjacent the floor of a room may 10 be drawn into a conduit and heated and then discharge adjacent the ceiling of the room thus bringing about circulation of air within the room for heating purposes.

A further object of the invention is to provide 15 a heating device for a room which will include a humidifier in order that the heated air will carry a certain amount of moisture when passing into the room.

A further object of the invention is to provide 20 a heating device which includes a serpentinized heated member with which air, drawn from a room adjacent the floor thereof, will contact before being ejected in heated condition into the room adjacent the ceiling thereof.

25 Other objects will appear hereinafter.

The invention consists in the novel combination and arrangement of parts to be hereinafter described and claimed.

The invention will be best understood by 30 reference to the accompanying drawings, showing the preferred form of construction and in which:

Fig. 1 is a fragmentary view of a wall of a room showing my invention associated therewith;

Fig. 2 is a sectional detail view taken substantially on line 2—2 of Fig. 1;

Fig. 3 is a sectional detail view taken substantially on line 3—3 of Fig. 2;

Fig. 4 is a sectional detail view taken substantially on line 4—4 of Fig. 2; and

Fig. 5 is a fragmentary part sectional detail view of a modified form of heating conductor embodied in the invention.

Referring more particularly to the drawings, a wall is indicated at 10. This wall includes a plastered surface 11 over a lath structure 12. These laths are ordinarily nailed to vertical studs 13 having their lower end portions secured to a sill plate 14 and

equally spaced apart by means of spacing studs 15. My improved heating device includes a conduit 16 which in the present instance is substantially rectangular in cross section and for mounting between two of the adjacent studs 13. The upper and lower end portions of the conduit 16 provide an entrance and exit mouths or openings 17 and 18 respectively. The entrance mouth 17 is normally covered by a plate 19 having a plurality of perforations 20 formed therein. A frame 21 is provided around the opening 22 in the wall 12 through which this entrance portion of the conduit 16 projects and mounted over this frame is a channel shaped frame 23 having its inner flange 24 overlapping the edge 25 of the entrance mouth. The plate 19 has its edge portions disposed upon this channel frame and these edge portions and the channel frame are secured to the frame 21 by screw elements 26. The exit mouth of the conduit 16 projects through an opening 27 formed in the wall 10 adjacent the ceiling and surrounding this opening is a frame 28. Mounted over this frame 28 is a channel shaped frame 29 similar to the channel shaped frame 23 and the flange 30 of this frame overlaps the edge 31 of the exit mouth of the conduit 16. A plate 32 is disposed over the exit mouth and this plate likewise has a plurality of perforations 33 formed therein. This plate has its edge portions 34 disposed upon the channel shaped frame and are secured together with the channel shaped frame to the frame 28 by means of screw elements 35.

The purpose of the structure thus far described is to admit air into the entrance mouth for passage upward through the conduit 16 and outwardly through the exit mouth 18 into the room in heated condition. The channel shaped frames 21 and 28 having their flanges 24 and 30 overlapping the edges of the entrance mouth and exit mouth of the conduit, will prevent escape of the heated air to the rear of the plaster surface of the wall.

The air is heated by a heating device which includes a conductor conduit 38 having a portion confined in the conduit 16 formed substantially serpentinized in shape whereby the air passing upwardly through the conduit 16

will come into contact with the protruding portions of the conduit 38 of the serpentine formation. The upper end portion of the conduit 38 leads to a chimney or the like to discharge obnoxious fumes generated by the heating element. This heating element is indicated at 39 and is of that type ordinarily used in connection with gas heaters and which are connected to a supply line 40, passage 10 through which being controlled by a shut-off valve 41. This heating unit also includes a pilot light 42 of any approved structure having its valve 43 disposed on the exterior side of the wall 10 for convenient operation. 15 The end portion 44 of the conduit 38 provides oppositely disposed notches 45 in which the unit 39 is disposed to support the conduit 38 with the cooperation of the studs 15 in the position shown in Fig. 2. At the lower 20 end portion of the conduit 38 there is provided a humidifying device 46, formed serpentine in formation, for flat position against the conduit 38. This humidifying device includes the pan 47 into which water 25 is delivered through the medium of a supply pipe 48. Passage through this pipe 48 is controlled by a valve head 49 fixed to an arm 50 of a bell crank 51 pivotally supported at 52 within the pan. The other arm 53 of this 30 bell crank carries a float 54 whereby when the water in the pan is low the bell crank will pivot downwardly to dispose the valve 49 from closing position with respect to the pipe 48, thereby to allow the admission of water 35 into the pan.

From the description herein taken in connection with the drawings, it will be manifest that a heating device of a simple structure is provided for heating rooms of residences, office buildings, and the like.

40 While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the 45 appended claim.

Having thus described my invention what I claim as new and desire to protect by Letters Patent is:

50 A heating device of the character stated including a substantially rectangular conduit adapted to be confined between adjacent studs and opposite faces of a wall, said conduit having an inlet opening at the lower end thereof and an outlet opening at the 55 upper end thereof, said openings extending through one of the faces of said walls, a second conduit confined within said first named conduit and being of less thickness but of substantially the same width as said first named conduit and having serpentine conve-

lutions formed therein, said second conduit extending throughout the extent thereof through the said first named conduit and terminating in a flue portion extended out through the upper end of said first named conduit, said second named conduit having an outwardly flared portion at the lower end thereof and having notches formed in the side walls of said outwardly flared portion, a heating element confined within said enlarged portion and extending out through said notches whereby the heat and fumes from said heating element will pass through said second conduit to heat the air surrounding the same in said first named conduit.

In testimony whereof I affix my signature.

RUDOLPH H. GUENTHER.
